UNITED STATES PATENT OFFICE.

JOHN J. FRANK, OF SCHENECTADY, NEW YORK, ASSIGNOR TO GENERAL ELECTRIC COMPANY, A CORPORATION OF NEW YORK.

TRANSFORMER.

No. 833,207.

Specification of Letters Patent.

Patented Oct. 16, 1906.

Application filed October 14, 1905. Serial No. 282,762.

To all whom it may concern:

Be it known that I, JOHN J. FRANK, a citizen of the United States, residing at Schenectady, county of Schenectady, State of New York, have invented certain new and useful Improvements in Transformers, of which the following is a specification.

It is a common practice at the present time to operate electrical apparatus—such as alternating-current transformers, condensers, &c.—with the apparatus immersed in a bath of insulating fluid, such as oil. Such a bath not only serves to convey away from the apparatus heat generated in it during operation, but may be relied upon to increase the effective insulation between parts subjected to differences of potential. When, as is usually the case with apparatus such as transformers operated at relatively high voltages, the bath of oil or the like is relied upon for its insulating properties, a fall in the level of the bath sometimes results in serious injury to the apparatus immersed in it, since different parts of the apparatus rising above the surface of the bath are no longer effectively insulated. Even if the insulation between the exposed parts is still great enough to withstand the difference of potential between the parts after the oil-level has fallen, the apparatus may be injured by such fall of level through an undue rise in temperature of the exposed portions which are no longer directly cooled by contact with the bath. The fall in level may result from various causes, such as evaporation of the fluid or leaks in the joints or fittings of the tank or receptacle containing the fluid. The interior of such apparatus is ordinarily from its very nature not subject to frequent inspections. It may happen, and frequently does in practice, that the level of the fluid slowly decreases to a dangerous extent without the knowledge of the attendants responsible for its care.

In order to guard against the evil consequences resulting from a fall in the level of the bath, I have provided protective devices for the apparatus which automatically come into operation when the level of the bath approaches the danger limit, and ordinarily serve not only to protect the apparatus against destruction, but by their operation form a means for indicating the condition of the fluid-level. I have advantageously used

sparking points or electrodes as such protective devices. These sparking points are arranged at or about the lowest level to which the bath may fall without endangering the safety of the apparatus. I connect these points to a suitable source of electric current, so that the difference of potential between the points is ordinarily insufficient to produce sparking between the points when immersed or submerged in the fluid, but sufficient to produce sparking when the points are no longer immersed in said fluid. The difference of potential between the points may be produced by connecting them into circuit with the apparatus immersed in the bath. For instance, when the apparatus in the bath is an alternating-current transformer I may connect the sparking points to terminals of one or more of the windings of the transformer, in which case when the fluid-level falls so that the sparking points are no longer separated by the normal insulation, the current normally passing through the transformer-winding will then pass through a circuit in shunt to the transformer-winding, including the sparking points and the arc between them. This not only serves to protect the winding of the transformer, but through its effect upon the external circuits serves to indicate to the attendant that the transformer is out of order.

The various features of novelty which characterize my invention are pointed out with particularity in the claims annexed to and forming a part of this specification. For a better understanding of my invention, however, reference may be had to the accompanying drawings and descriptive matter, in which I have illustrated and described my invention as applied to a modern oil-cooled insulated transformer.

Of the drawings, Figure 1 represents an elevation, with parts broken away and in section, of a transformer embodying my invention. Fig. 2 is a sectional elevation illustrating a detail of construction. Fig. 3 is a sectional plan on the line 3 3 of Fig. 1. Figs. 4, 5, and 6 are diagrams illustrating different arrangements of high-potential windings of the transformer and the protective device, and Fig. 7 illustrates a modification.

In the drawings, 1 represents the case or tank comprising a body portion 2, base 3, and top or cover 4. The transformer proper, which is placed in the tank, comprises a core

5, on the two parallel legs of which are placed the windings of the transformer. The windings of the transformer comprise a low-voltage coil 6 on each leg of the core and a pair 5 of high-voltage coils 7 and 8 on one leg of the core and a pair of high-voltage coils 9 and 10 on the other leg of the core. The core and its windings are supported by members which engage the tank and may be in the form of 10 wooden bars 11. The high-voltage terminals of the transformer comprise conducting-rods 12 and 13, brought out through the cover of the case through bushings, or tubular insulators 14, which may be similar to those 15 shown in my Patent No. 792,016, granted June 13, 1905.

Brackets 15, secured to bars or beams 11 at the upper and lower ends of the core, support tubular insulators 16 and 17, which may be generally similar in construction to the insulators 14. In the particular construction illustrated there are six of these insulators 16 in front of the transformer, as seen in Fig. 1, and six insulators 17 directly behind the transformer. The insulators 16 on the front side of the transformer, as seen in Fig. 1, support vertical conducting rods or bars 18, 19, and 20. Similar rods or bars 21, 22, and 23 are supported by the insulators on 25 the other side of the transformer. To the lower end of each vertical conducting-rod is secured an extension 24 by a collar 24'. The extensions 24 are of some suitable insulating material possessing considerable mechanical 30 strength. The vertical conducting-rods are each provided with a collar or enlargement 25, which engages the upper end of its upper supporting-insulator 16 or 17. A nut 26, which may be of suitable insulating material, 35 is threaded on the lower end of each extension 24. Each nut engages the lower ends of the appropriate lower insulators 16 or 17. It will thus be observed that each member comprising a conducting rod or section and a section 40 of insulating material is secured in place and supported by a pair of upper and lower insulators 16 or 17.

The upper ends of the vertical conducting-rods are threaded and carry threaded brackets 50 27. These brackets, which can be adjusted both angularly and longitudinally with respect to the vertical conducting-rods supporting them by reason of their threaded arrangement, may be locked in any desired 55 position with respect to the rods by lock-nuts 28. Each bracket 27 is provided with a horizontally-extending arm formed with a threaded socket in which is screwed or threaded one end of a connecting-rod, the other 60 end of which terminates in a ball sparking point or electrode. It will thus be observed that the vertical conducting-rods 18, 19, 20, 21, 22, and 23 are electrically connected to the 65 sparking points or electrodes 29, 30, 31, 32, 33, and 34, respectively.

The lower end of the conducting-rod 12 has threaded upon it an arm 35, provided with a threaded socket in which is screwed the end of a rod carrying a sparking ball 36. A sparking ball 38 is supported in an arm 37, 70 similarly secured to the conducting-rod 13. The terminals of the high-potential windings 7, 8, 9, and 10 of the transformer are intended to be connected to the vertical conducting-rods 18, 19, 20, 21, 22, and 23 and 75 the terminal conductors 12 and 13 in various ways, depending upon the conditions under which the transformer is to operate, and the rods 18, 19, 20, 21, 22, and 23 may be interconnected in various ways. 80

In Fig. 4 the windings 7, 8, 9, and 10 are shown all in series. In this case the sparking points 36 and 29 are in shunt to the winding 7. The sparking points 32 and 30 are in shunt to the winding 8. The sparking points 85 33 and 31 are in shunt to the winding 9, and sparking points 34 and 38 are in shunt to the winding 10.

In Fig. 5 the windings 7 and 8 are in multiple with each other and in series with the 90 windings 9 and 10, which in turn are in multiple with each other. In this case the windings 7 and 8 are each protected by the sparking points 36 and 29 and also by the sparking points 32 and 20. Similarly the windings 9 and 10 are each protected by the 95 sparking points 33 and 31 and by the sparking points 34 and 38.

In Fig. 6 the windings 7, 8, 9, and 10 are all connected in multiple and each coöperating pair of sparking points serve to protect each and every one of the windings. Of course it will be understood that when the coils are all in multiple operating sparking points might be eliminated with safety, but 105 inasmuch as the windings 7, 8, 9, and 10 of a particular transformer are intended to be connected at various times in the forms shown in Diagrams 4, 5, and 6 it is preferable to provide the plurality of sparking points 110 shown, though with the connections shown in Fig. 4 one pair and with the connections shown in Fig. 5 two pairs of coöperating 115 sparking points would ordinarily protect the entire high-voltage winding against a fall in level of the insulating fluid in which the transformer is immersed.

It will be understood that the sparking points can be adjusted to bring each coöperating pair the desired distance apart and the 120 proper distance above the transformer. It is usually desirable to have the sparking contacts some little distance above the upper end of the transformer. One of the reasons for this is that the surface of the insulating fluid on account of foreign matter which may be carried on it is apt to be of better conductivity for high-potential discharges than is air itself.

The normal level of the oil-bath in the cas- 130

ing is indicated by the line A A. When the level of insulating fluid falls to expose or partly expose the sparking points, current will pass in shunt to the windings through circuits including the sparking points and arcs between them. This will protect the windings by diverting the current from them, and will indicate to the attendant by the disturbance produced in the voltage of the external circuits that the transformer needs attention.

In order to limit the current-flow in shunt to the windings when arcing occurs between electrodes, I sometimes find it advantageous to insert a resistance in series with each pair of coöperating sparking electrodes. In Fig. 7 I have illustrated such an arrangement where resistances 39 are in series with the electrodes 36 and 29.

While the form of my invention disclosed in detail has been found to give excellent results in practice, it will be understood that many changes may be made in the form of invention disclosed without departing from the spirit, and that certain features of my invention may be employed without a corresponding use of others, and I do not wish the claims hereinafter made to be limited to the particular embodiment disclosed more than is made necessary by the state of the art.

What I claim as new, and desire to secure by Letters Patent of the United States, is—

1. In combination, a case containing a bath of insulating liquid, a winding immersed in said bath, means for creating a difference of potential between the terminals of said winding, a pair of coöperating sparking points or electrodes connected to the terminals of said winding and arranged below the normal surface of said fluid and separated from each other by a distance such that when covered by said liquid the normal potential existing between the terminals of said winding will be insufficient to cause a discharge between the points but so that when not covered by the liquid a discharge will take place between them.

2. In combination, a body of insulating fluid, a winding immersed therein, means for creating a difference of potential between different portions of said winding, and means automatically responsive to a change in level of said body of fluid for diminishing said difference of potential when the level of the fluid falls to a predetermined stage.

3. In combination, a body of insulating fluid, a winding immersed therein, means for creating a difference of potential between different portions of said winding, and sparking points connected to said portions, said sparking points being normally immersed in said fluid and separated from each other by a distance such that when immersed the difference of potential between them will not cause a discharge so that when not im-

mersed in said fluid said potential difference will cause a discharge between the points.

4. In combination, a body of liquid of variable level, and means for indicating a variation in said level comprising a pair of sparking points or conductors adapted to be immersed in said liquid at one stage or level and exposed at another stage or level, and means for creating a difference of potential between said electrodes great enough to cause a discharge at one of said stages, but not great enough to cause a discharge at the other of said stages.

5. In combination, a body of insulating fluid, a core and a winding thereon normally submerged in said fluid, electrodes or sparking points connected to different portions of said winding and normally submerged in said fluid, but becoming exposed upon a predetermined fall in the level of said fluid, and means for adjusting the distance between said electrodes.

6. In a transformer, a case or receptacle, a body of insulating fluid contained therein, a core and a winding thereon normally submerged in said fluid, and sparking points or electrodes electrically connected to said winding so that a difference of potential between them exists, said electrodes being normally submerged below the surface of the insulating fluid but becoming exposed upon a predetermined fall in level of said fluid, and being separated by a distance such that when submerged said difference of potential will not cause a sparking discharge between them while when exposed it will.

7. In a transformer, a core, windings thereon, insulators supported at opposite ends of said core, and a member supported by said insulators, said member comprising a portion of conducting material, another portion of insulating material, one of said portions engaging one insulator and the other of said portions engaging the other of said insulators, and a sparking point or electrode carried by said conducting-section, and a connection between said section and said winding.

8. In an oil-cooled transformer, a case, a body of oil contained therein, a core and high and low potential windings thereon normally submerged in said oil, said high-potential winding being formed in sections adapted to be connected in various relations with each other, and a pair of coöperating electrodes or sparking points connected in shunt to each section, said electrodes being normally submerged in the oil but becoming exposed upon a predetermined fall in the level of the oil, each coöperating pair of electrodes being separated by a distance such that when submerged the normal difference of potential existing between them will not cause a discharge, but when exposed such difference of potential will cause a discharge.

9. In an oil-cooled transformer, a case, a body of oil contained therein, a core and high and low potential windings thereon normally submerged in said oil, said high-potential winding being formed in sections adapted to be connected in various relations to each other, a pair of coöperating electrodes or sparking points connected in shunt to each section, said electrodes or sparking-points being normally submerged in the oil but becoming exposed on a predetermined fall in the level of the oil, and means for adjusting the distance between each coöperating pair of electrodes.
10. In combination, a body of insulating fluid, a core and a winding thereon normally submerged in said fluid, electrodes or sparking points connected to different portions of said winding and normally submerged in said fluid, but becoming exposed upon a predetermined fall in the level of said fluid, and a resistance in series with said electrodes.

In witness whereof I have hereunto set my hand this 13th day of October, 1905.

JOHN J. FRANK
